UNITED STATES PATENT OFFICE.

FREDERICK W. PARSONS, OF ELMIRA, NEW YORK, ASSIGNOR TO INGERSOLL-RAND COMPANY, OF JERSEY CITY, NEW JERSEY, A CORPORATION OF NEW JERSEY.

VERTICAL COMPRESSOR UNIT.

1,418,202.

Specification of Letters Patent. Patented May 30, 1922.

Application filed May 20, 1921. Serial No. 471,138.

To all whom it may concern:

Be it known that I, FREDERICK W. PARSONS, a citizen of the United States, a resident of Elmira, county of Chemung, and 5 State of New York, have invented a certain Vertical Compressor Unit, of which the following is a specification accompanied by drawings.

This invention relates to compressors, but 10 more particularly to compressor units of the vertical type and the objects of the invention are to produce such units capable of being readily assembled in multi-stage machines occupying relatively small floor space, simple and compact in design and strong and rugged in construction and having substantially all their operating parts readily accessible for assembling, disassembling, inspection and cleaning.

20 Further objects of the invention are to enable a frame or column for a compressor unit to be constructed with a removable front section forming a combination cover plate and front support, which may be removed when desired without deranging or disturbing the remainder of the unit. The accompanying drawings show one preferred form of the invention in which,

Figure 1, is a side elevation partly in longitudinal section of a multi-stage compressor including two compressor units.

Figure 2, is an enlarged transverse sectional elevation of one unit with the combination cover plate and front support removed, and

Figure 3, is a transverse sectional elevation of the removable combination cover plate and front support.

Referring to the drawings, Figure 1 illustrates a two stage vertical compressor mounted on the foundations A and in this instance the compressor units are shown mounted at each side of the pit B in position to be driven by a suitable electric motor C located in the pit between the compressor units. The motor C may for instance be a synchronous motor, as shown, having a separately excited field, and a fly wheel D, which also forms an exciter pulley. The motor 45 and the fly wheel are mounted on the main shaft E for driving both compressor units. It is to be understood, however, that Figure 50 55 is to be taken as illustrative only, showing a suitable form of motor drive, and if desired the compressor units could be mounted

side by side and driven in any suitable manner instead of by means of a central drive.

Each unit is provided with a base F preferably having an oil sump or basin G in its bottom, separated from the remainder of the base by means of the filter screen H. Only one compressor unit will be described in detail, since the other is substantially similar, except for the fact that one is a low pressure unit and the other a high pressure unit. In the example shown in the drawings, the low pressure cylinder J and intake K are shown at the left and the high pressure cylinder L and discharge O are shown at the right with their respective inner and outer air heads P and Q, and R and S.

Referring more particularly to the low pressure-unit, illustrated in detail in the figures, the base F is provided with the bearing T for the main shaft E and an open frame or column U is suitably mounted on the base F as by means of the bolts V, and is adapted to support a compressor cylinder as for instance the low pressure cylinder J with its air heads P and Q. The air heads carry any suitable form of inlet valves W and discharge valves X, in this instance valves of the plate type being shown, the cylinder J has the reciprocating piston Y and piston rod Z.

The main frame or column U, as shown, is formed with the inner vertical web a and the overhanging cap portion b. The vertical web portion a carries the cross head guide c suitably bolted thereto for guiding the cross head d to which the piston rod Z is suitably connected. The connecting rod e, as shown, is suitably connected to the cross head pin f at its upper end, and to the crank pin g of the crank h on the main shaft E at its lower end. By means of this construction, the cross head d is guided on the guide c supported on the inner wall or web of the main frame or column U and the cross head, connecting rod, crank and main shaft are readily accessible for all purposes.

In order to close the front opening of the column U a combination cover plate and front support j, is provided having side webs or portions k and provided with top and bottom flanges o and p having bolt holes q and s adapted to register with the bolt holes t and u respectively in corresponding portions of the top b of the column U and the top of the base F, so that when the cover plate j is

placed in position on the base F and beneath the top b of the column, it may be securely bolted in position, closing the opening in the column and forming a support for the front of the column in addition to acting as a closure to enclose the operative parts within the column. It is to be understood, however, that the principal support for the operative machinery within the column is afforded by the column itself as constructed and designed.

Each main frame or column U is preferably provided with a bracket v for supporting a suitable intercooler w adapted to be secured in any suitable manner to the brackets, and connected to the low and high pressure cylinders by means of suitable piping x. In Figure 2 the discharge y of the low pressure cylinder is shown connected in the intercooler w and the arrangement of the intercooler extending longitudinally between the compressor units and connected thereto by means of the brackets v, serves to strengthen and brace the entire structure and reduce vibration.

A suitable gear oil pump 2 carried by the pump support or case 3 in the base F, the details of which pump need not be described in detail, is adapted to be driven from the crank h in any suitable manner, and may be connected to suck oil from the oil sump or basin G by any suitable means (not shown). An oil ring 4 may be provided on the main shaft E adjacent the main bearing T and a removable main bearing shield 5 having a hand hole cover 6, is provided over the main bearing. The oil may be pumped up by the pump 2 by connections (not shown) to the trough 7 in the cap portion b of the column from which the oil passes to the cross head guide and cross head and other connected operative parts of the machinery.

In addition to the removable combination cover plate and front support j affording accessibility to the interior of the column, and the removable main bearing shield 5 affording accessibility to the main bearing, additional removable cover plates 8 and 9 are provided at each side of the column and removable cover plates 10 and 11 are provided on the cap portion of the column to afford accessibility to the piston rod gland 12, and other adjacent parts. By removing the cover plates and main bearing shield for the column, the main shaft E may be assembled and disassembled in the machine in a convenient manner and with a minimum of labor. While the machine is in operation any desired portion may be inspected at will, by removing the appropriate cover plate.

I claim:

1. A supporting frame for a vertical compressor unit, comprising a hollow base affording a bearing for a main crank shaft, a main frame mounted on said base and con-

sisting of a column open at one side and having inner and outer walls at the opposite side, a top portion overhanging the open side of the column, and a closure for said open side in the form of a removable section of the side of the column constituting a combination cover plate and front support, the inner vertical wall of the column affording means for supporting a cross head guide, whereby the front of the column may be removed without disconnecting or disturbing the operative parts of the machine.

2. A supporting frame for a vertical compressor unit, comprising a hollow base affording a main bearing for a crank shaft, a main frame mounted on said base and consisting of a column open at one side and having inner and outer walls at the opposite side, a top portion overhanging the open side and a closure for said side in the form of a removable section of the side of the column constituting a combination cover plate and front support, a removable main bearing shield carried by the base and column, and removable cover plates for the ends of the column and for the ends of the top portion of the column to afford accessibility to the interior in addition to the accessibility afforded by the removable combination cover plate and front support.

3. A vertical compressor unit comprising a base having a main bearing, a crank shaft carried in said bearing, a main frame mounted on said base in the form of a column open at one side and having inner and outer walls at the opposite side, and a top portion overhanging the open side of the column, a closure for said open side of the column consisting of a removable combination cover plate and front support adapted to be secured to the column and to the base, a compressor cylinder and air heads supported by the top portion of the column, a reciprocating piston for said cylinder, a crosshead guide secured to the inner vertical wall of the column, and operative connections between the compressor piston and the main crank shaft including a crosshead sliding in said crosshead guide.

4. A vertical compressor unit comprising a base having a main bearing, a crank-shaft and crank carried by said main bearing, a main frame in the form of a column supported on said base and having inner and outer walls at one side and an overhanging top portion, the opposite side of the column being open, and a removable combination cover plate and front support fitting the open side of the column and forming a closure for the said side, a crosshead guide supported on the inner vertical wall of the column, a crosshead sliding thereon, a compressor cylinder and air heads supported upon the top portion of the column, a piston and piston rod connected to said crosshead

and a connecting rod connecting the cross-head and crank.

5. A multi-stage vertical compressor consisting of a plurality of vertical units assembled side by side and adapted to be driven from a common crank shaft, each unit comprising a hollow base affording a bearing for a driving shaft, a main frame mounted on each base in the form of a column open at one side and having inner and outer vertical walls at the opposite side, and a top portion overhanging the open side of the column, a closure for each of said open sides in the form of a removable section of the side of the column consisting of a combination cover plate and front support, compressor cylinders and air heads mounted in the top portions of the columns, crosshead guides secured to the inner vertical walls of the columns and operative driving connections between the main crank shaft and the pistons of each cylinder including crossheads sliding in said crosshead guides.

6. A multi-stage vertical compressor consisting of a plurality of vertical units assembled side by side and adapted to be

driven from a common crank shaft, each unit comprising a hollow base affording a bearing for a driving shaft, a main frame mounted on each base in the form of a column open at one side and having inner and outer vertical walls at the opposite side, and a top portion overhanging the open side of the column, a closure for each of said open sides in the form of a removable section of the side of the column consisting of a combination cover plate and front support, compressor cylinders and air heads mounted in the top portions of the columns, crosshead guides secured to the inner vertical walls of the columns, operative driving connections between the main crank shaft and the pistons of each cylinder including crossheads sliding in said crosshead guides, brackets on the outer vertical walls of the columns, an inter-cooler carried by said brackets and extending longitudinally of the compressor units, and fluid connections between the compressor cylinders and the intercooler.

In testimony whereof I have signed this 55 specification.

FREDERICK W. PARSONS.
